SUPPORT AND REEL STRUCTURE FOR
TABLE TENNIS NETS

Jacob Hillson, Brookline, Mass., assignor to Harvard Specialty Mfg. Corp., Cambridge, Mass., a corporation of Massachusetts

Application March 29, 1938, Serial No. 198,711

4 Claims. (Cl. 273—30)

This invention relates to a support and reel structure for a net such as is used in playing the game known as table-tennis or "ping-pong". It deals more especially with a structure that enables maintenance of the net in the desired taut condition, irrespective of variations in the width of the table on which the net is installed. The structure of the present invention makes possible the fabrication of a net of a width ample for the 10 widest table used for the game, since it is capable of taking up such net slack as is incident to the installation of the net on narrower tables.

Not only is the support and reel structure hereof characterized by its simplicity or fewness of 15 parts, compactness, and ease and economy of manufacture, but it is a unitary structure devoid of loose parts and can be readily secured to a table and operated without tools to take up any net slack. Generally stated, such structure comprises a frame inclusive of means for securement 20 to a table, a post upstanding from the frame and on which the usual tubular seam of the net is loosely or removably receivable, means for releasably holding the seam against slippage upon rotation of the post, and means normally holding 25 the post against rotation in the frame but being manually releasable to enable the rotation of the post and the winding thereon of net slack. The means for releasably holding the seam against slippage upon rotation of the supporting 30 post may advantageously take the form of an elongated member of U-shape cross section pivotally secured at its lower end to the post and swingable to an upstanding position so as partially encompass the post and thus hold the 35 seam against slippage upon rotation of the post.

With the foregoing and other features and objects in view, the invention hereof will now be described in further detail with particular reference to the accompanying drawing, wherein,—

Figure 1 shows in perspective a net installed 40 on a table with one end of the net supported by a support and reel structure embodying the instant invention.

Figure 2 is a section through the frame of such structure.

Figure 3 depicts in disassembled relationship those portions of the post and frame that co-operate to hold the post normally against rotation in the frame.

Figure 4 shows in perspective the net-receiving portion of the post with the tubular end-seam of the net received thereon and just before the member for releasably holding the seam against slippage has been brought into seam-holding position.

Figure 5 represents a section on the line 5—5 of Figure 4.

Figure 6 is a similar view but after the seam-holding member has been brought into seam-

holding position and the post has been rotated somewhat to take up net slack.

As appears in Figures 1 and 2, the structure hereof comprises a substantially U-shaped frame 10 engageable over the edge portion of a table 11 with its legs 10a and 10b extending substantially parallelly to the substantially horizontal table surfaces. The frame preferably includes a bar 12 bridging its legs and secured thereto at regions well removed from the bend or closed end portion 10c. The bar 12 serves not only as a brace for the frame legs 10a and 10b but also as an abutment bearing against the side edge of the table and thus stopping undesirable inward movement of the frame relative to the table. 15 The frame also includes means for securement to the table as in the form of a screw element 13 threaded through the frame leg 10b at a region somewhat outwardly of the bar 12. The inner end portion 13a of the screw element is preferably of enlarged cup shape so as to engage firmly the under surface of the table, as shown in Figure 1, whereas the outer end portion of the screw element may be of enlarged eye-shape 13b to permit easy grip and turning by the fingers.

The post 14 on which the tubular end-seam 15 of a table-tennis net 16 is loosely receivable, as illustrated in Figures 1 and 4, is substantially vertically upstanding from the frame 10. Such post is shown as comprising a lower end portion 14 passing through suitable openings in both legs of the frame 10 adjacent to the closed end portion 10c and extending somewhat beyond the lower leg 10b of the frame with its extension 14a equipped with one or more lugs 14b permitting limited upward axial movement of the post. Downward axial movement of the post as well as rotation of the post is shown as being prevented by one or more lugs 14c protruding therefrom into one or more complementary recesses 15 in 40 the upper surface of the frame leg 10a immediately adjacent to the opening 0 through which the post passes. The lugs 14c may be normally held in the complementary recesses 15 by a suitable spring, preferably a compression coil spring 26 45 encompassing the post portion immediately below the frame leg 10a and confined in position under suitable pressure with its uppermost convolution bearing against the lower surface of such frame leg and its lowermost convolution bearing against an annular ledge 17 suitably fixed to the post. By bearing on the lower end of the post against the pressure of the spring 26 so as to effect further compression thereof, as with the thumb, until the lugs 14c have been disengaged from their complementary recesses 15, it is possible to rotate the post 14 to any desired extent. However, unless the tubular end-seam 15 of the net received on the post is kept from slipping during the rota-

tion of the post, such slack as may exist in the net cannot be taken up.

A simple and highly effective means for releasably holding the tubular end-seam of the net against slippage as its supporting post is being rotated for the purpose of taking up the net slack may take the form of an elongated member 18 of U-shaped cross-section, whose lower end portion may consist of a yoke 19 pivotally secured, as at 20, to the post. After the tubular end-seam 15 of the net has been slipped over the post 14 with its lower end in between the yoke arms 19 immediately above the pivot 20, the member 18 is swung upwardly and pushed into position over the seam and post. The space or gap between the walls of the member 18 is such that in being pushed or forced into position over the seam 15, it tightly engages and compresses the fabric constituting such seam and the seam is held in between such member and the post under sufficient friction to obviate slippage thereof upon rotation of the post. Accordingly, once the member 18 is in position over the tubular end-seam of the net, the post may, as already indicated, be moved axially upwardly with the thumb of one hand to a position permitting of its rotation and then rotated with the fingers of the other hand to wind or take up any net slack thereon and on such member, as illustrated in Figures 1 and 6. The post may then be released so as to enable the spring 26 automatically to force it downwardly and restore it to the position where the lugs 14c engage the complementary frame recesses 15 and thereby prevent unwinding of the previously taken-up net slack. So as to facilitate turning movement or rotation of the post by the fingers, its upper end portion 14d may be fashioned as a somewhat enlarged knurled head.

While it is possible to use a support and reel structure embodying the invention hereof for each of the tubular end-seams of a table-tennis net, yet it is necessary to provide only one such structure for the proper installation of the net. It is for this reason that the completely installed net depicted in Figure 1 comprises the support and reel structure hereof only on one side of the table. The other side of the table may have fastened thereto any suitable or conventional support, for instance, one comprising a U-shaped frame 21 from which is upstanding a post 22 for loosely receiving the other tubular end-seam 23 of the net 16. The lower end of the seam 23 may rest on the bend of a hook element 24 projecting upwardly from the post 22.

It is to be understood that the inventive principles hereof might be embodied in support and reel structures other than the typical one specifically described and illustrated herein and that the appended claims should be construed as broadly as the prior art permits.

I claim:

1. A support and reel structure for a table-tennis net equipped with a tubular end-seam, comprising a frame structure inclusive of means for securing to a table, a post upstanding from said frame and on which said tubular seam is loosely receivable, an elongated member of U-shaped cross section pivotally secured at its lower end portion to said post and swingable to an upstanding position so as partially to encompass said post and hold said tubular seam firmly against slippage upon rotation of said post, and means normally holding said post against rotation in said

frame but being releasable to enable the rotation of said post and the winding thereon of net slack.

2. A support and reel structure for a table-tennis net equipped with a tubular end seam, comprising a frame inclusive of means for securing to a table, a post upstanding from said frame and on which said tubular seam is loosely receivable, an elongated member of U-shaped cross section pivotally secured at its lower end portion to said post and swingable to an upstanding position so as partially to encompass said post and hold said tubular seam firmly against slippage upon rotation of said post, said post comprising a lug and said frame comprising a stop element normally engaged by said lug to prevent rotation of said post but said post being axially movable to a position resulting in disengagement of said lug and said stop element to permit rotation of said post, and spring means for automatically restoring said post to a position resulting in reengagement of said stop element by said lug.

3. A support and reel structure for a table-tennis net equipped with a tubular end-seam, comprising a U-shaped frame engageable over the edge portion of a substantially horizontal table 25 with its legs extending substantially parallelly with said table, said frame including means for securing to said table, a post upstanding from said frame and on which said tubular seam is receivable, said post comprising a lower end portion passing through openings in both legs of said frame and extending somewhat beyond the lower leg of said frame, a lug projecting from said post, a recess in the upper leg of said frame in which said lug normally engages and thereby prevents rotation of said post, a ledge on said post in between the legs of said frame, a compression spring confined in between the upper leg of said frame and said ledge, said post being axially movable in an upward axial direction to disengage 40 said lug from said recess and thereby permit rotation of said post, and means for releasably holding said tubular seam against slippage upon rotation of said post and thereby enabling the winding on said post of net slack.

4. A support and reel structure for a table-tennis net equipped with a tubular end-seam, comprising a U-shaped frame engageable over the edge portion of a substantially horizontal table with its legs extending substantially parallelly 50 with said table, said frame including means for securing to said table, a post upstanding from said frame and on which said tubular seam is receivable, said post comprising a lower end portion passing through openings in both legs of said frame and extending somewhat beyond the lower leg of said frame, a lug projecting from said post, a recess in the upper leg of said frame in which said lug normally engages and thereby prevents rotation of said post, a ledge on said post in between the legs of said frame, a compression spring 55 confined in between the upper leg of said frame and said ledge, said post being axially movable in an upward axial direction to disengage said lug from said recess and thereby permit rotation of said post, and an elongated member of U-shaped cross section pivotally secured at its lower end portion to said post above the upper leg of said frame and swingable to an upstanding position so as partially to encompass said post and hold said 70 tubular seam firmly against slippage upon rotation of said post and thereby enabling the winding on said post of net slack.

JACOB HILLSON.
